UNITED STATES PATENT OFFICE.

JACK JOSEPH RENIE, OF LOS ANGELES, CALIFORNIA.

DESIGN FOR AN AEROPLANE TOY.

Application filed October 3, 1927. Serial No. 23,612. Term of patent 3½ years.

To all whom it may concern:

Be it known that I, JACK J. RENIE, a citizen of the United States, residing at Los Angeles, in the county of Los Angeles and State of California, have invented a new, original, and ornamental Design for an Aeroplane Toy, of which the following is a specification, reference being had to the ac-

companying drawing, forming part thereof.

Fig. 1 is a perspective view of an aeroplane toy, showing my new design.

Fig. 2 is a front view of the same.

I claim:

The ornamental design for an aeroplane toy substantially as shown.

JACK JOSEPH RENIE.
